UNITED STATES PATENT OFFICE.

JOHN F. OHMER, OF DAYTON, OHIO, ASSIGNOR TO OHMER FARE REGISTER COMPANY, OF ROCHESTER, NEW YORK.

FARE-REGISTER.

No. 892,877.

Specification of Letters Patent.

Patented July 7, 1908.

Application filed May 28, 1906. Serial No. 318,994.

To all whom it may concern:

Be it known that I, JOHN F. OHMER, a citizen of the United States, residing at Dayton, in the county of Montgomery and State of Ohio, have invented certain new and useful Improvements in Fare-Registers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in fare registers and comprises a single fare, register, or a register adapted to take care of a single denomination of fare in duplicate; to indicate such fare by means of a permanent indicator; to furnish separate records from the duplicate printing counters, and to record and indicate the total fares or passengers upon a separate bank of counters which are actuated simultaneously with each operation of the duplicate printing counters. One of the records is taken by the conductor or conductors operating the register for a definite period or periods, and the conductors alone have access to this record; the other record is taken by the cashier, inspector or other authorized person, and such person alone has access to such record. The record taken by the cashier or inspector may cover a period of a day or a longer period, and it will show the work of the different conductors operating the register from the time the last record was taken and removed by the cashier or inspector. These two records, to-wit—the conductor's record and the cashier or inspector's record are duplicates and are delivered into separate compartments.

In addition to the means for registering the fares collected in duplicate, and for taking in duplicate, printed records of such fares, means are provided for showing upon such duplicate records other miscellaneous data, such for example, as the month and the day, the number of the register, the number of fares collected by each conductor and the denomination of the fare.

In the drawings I have shown one of the statements as bearing the conductor's identification mark, and the other statement to-wit—the conductor's statement, as containing his signature and by which it is identified; it will

be readily seen, however, that both statements may contain an impression of the conductor's identification mark by duplicating the conductor's identification key, and providing a suitable opening for it.

The present invention relates to the type of fare register shown and described in United States Letters Patent No. 646,757 granted to myself April 3rd, 1900, and United States Letters Patent No. 694,322 granted to myself and others jointly with me, February 25, 1902. Registers of the type disclosed in the above-mentioned patents provide means for registering a multiplicity of different denominations of fares, and for taking printed records showing a classification of the different denominations of fares collected, with other miscellaneous data, such for example, as the conductor's identification mark, the number of the register, the months and the days thereof, and the trip numbers.

The present invention differs from the above results to this extent, that a single denomination of fare is recorded in duplicate and duplicate records are taken from the counters, such records being intended for different authorized persons, to-wit—the conductor or conductors collecting the fares, and the cashier or inspector. The duplicate records also show the number of fares collected in duplicate, and the denomination of the fares.

The present invention also comprises means for separating and inclosing in separate compartments the duplicate records, one of such compartments being designed to receive the conductor's record and to which he alone has access, and the other compartment being designed to receive the cashier or inspector's record, and to which the cashier or inspector alone has access.

The invention further comprises means for simultaneously actuating the duplicate counters from a single operating device, such operating device also serving to simultaneously actuate a corresponding set of counters which are otherwise known as "trip" or "passenger" counter wheels.

The identifying means associated with the register record are fully described and shown in Letters Patent No. 694,322 hereinbefore referred to, and the means for identifying such records with the dates and other matter are more particularly shown and described in Letters Patent No. 646,757 hereinbefore

referred to; it will therefore, not be necessary to make more than an incidental mention of these features in connection with their embodiment in the present invention which 5 contemplates the provision of means whereby one or more conductors are enabled to take their individual records from the register, the same to be turned over to the cashier with the fares collected, and with the 10 knowledge that a duplicate of such record remains in the register, and that such duplicate record may thereafter be checked or audited against the several conductors' records previously taken and removed.

15 In the accompanying drawings—Figure 1, is a perspective view of a one fare register constructed in accordance with my invention. Fig. 2, is a front elevation of the same with the casing shown in section. 20 Fig. 3, is a sectional side elevation on the line $x-x$ of Fig. 2. Fig. 4, is a detail view of the impression devices for taking the duplicate records from the printing counters. Fig. 5, is a detail perspective view of the duplicate fare-denomination printing wheels. 25 Fig. 6, is a detail view of the primary actuating shaft of the duplicate-printing counters. Fig. 7, is a view of the record as taken by a conductor. Fig. 8, is a duplicate of 30 such record as taken by the cashier or inspector. Figs. 9 and 10 are detail views of the transfer wheels of the duplicate-printing counters. Fig. 11, is a side view of the register with the casing removed. Fig. 12, is a 35 detail view of the key for actuating the eccentric bar of the printing or impression devices.

In a detail description of the invention, similar reference characters indicate corresponding parts.

40 The casing 1 is of suitable design and size to accommodate the capacity of the machine or register, which is for a single fare, such for example, as five cent cash fares. 45 The front face of the casing has an upper sight opening 2 through which is visible the numbers appearing on the trip or passenger indicator wheels to be again referred to. And another sight opening 3 through which 50 the permanent fare indicator 3^a is visible, such fare indicator bearing the inscription "cash" indicating that the register is adapted for registering a single denomination of fare, for example, cash fares. This permanent indicator 3^a may be replaced by a permanent indicator of any other class of fare, for example, tickets, in which case the fare counters would be utilized to register ticket collections alone. The lower portion of the 55 casing is suitably enlarged to accommodate the printing attachments which will be more particularly referred to hereinafter. The interior of the lower portion of the casing is provided with two separated compartments 6 and 7, the latter being adapted to contain

one of the duplicate records such as is shown in Figs. 7 or 8, and the other compartment being adapted to contain the other duplicate record. Access is obtained to these compartments through doors 4 and 5 which are 70 secured by means of suitable locks 4^a and 5^a.

The primary actuating ratchet wheel 11 is fast upon shaft 8 having suitable bearings in the framework. Engaging this ratchet wheel 11 is a single ratchet pawl 14 carried 75 upon a supporting arm 12 which is loosely mounted upon the shaft 8 adjacent to said ratchet wheel. Engaging the pawl support 12 to raise and lower it and herewith the pawl 14, is a single actuating member 13 80 having projections 13^a between which the free end of the pawl support 12 is projected.

Projecting from the rearward side of the actuating member 13 is a lug 13^b, said lug projecting through a slot 1^a in the rear side 85 of the inclosing case. This lug or projection 13^b is engaged by the operating means (not shown) and through which said actuating member 13 is lifted to impart movement to the ratchet wheel 11 and shaft 8 through the 90 pawl 14. The ratchet wheel 11 has fixed to one side thereof a ten toothed wheel 16 and a single toothed wheel 22; the ten toothed wheel imparts movement to the unit printing counter 23, and the single 95 toothed wheel 22 transfers to the tens printing counter 24. The transfer wheels 29 and 30 are loose on the shaft 8 and through these wheels 29 and 30 the hundreds and thousands printing counters 25 and 26 are actuated 100 in a well known manner to count the fares thereon. These printing counters are loose upon their supporting shaft 9, and upon said shaft there is a duplicate set of such printing counters which are identically 105 the same in every particular with the exception of the ratchet wheel 11 through which the shaft 8 is actuated by the pawl 14. The actuating ten toothed wheel 16^a of the 110 duplicate counters is fast upon the shaft 8 and imparts movement to the duplicate unit wheel 23^a. Attached to said wheel 16^a is a single toothed wheel 22^a which imparts movement to the tens printing counter 24^a. The hundreds and thousands printing counters 25^a and 26^a are actuated through the 115 transfer wheels 30^a and 29^a which are loose upon the shaft 8. 78 and 78^a designate devices for printing the register number upon the duplicate records, the mark being indicated on the records by 17; these devices are fast on shaft 9.

120 Interposed between the duplicate printing counters upon shaft 9 are duplicate printing wheels 10 and 10^a which are united by 125 means of a sleeve 15. The peripheries of these printing wheels are provided with printing characters indicating the denomination of fare which is registered upon the duplicate printing counters, for example, cash 130

fares, tickets, transfers or any other denominations of fares for which the duplicate counters are utilized.

In the present instance the duplicate printing counters are utilized for registering cash fares, it will therefore be understood that these printing wheels 10 and 10^a are arranged in a position to print the word "cash" or any abbreviation thereof which will show upon the printed record or records that the fares counted upon the printing counters are of that denomination. These fare denomination printing wheels 10 and 10^a do not rotate but are made stationary by being attached by means of a screw 17 to a web 18 which extends between collars 19 and 19^a which loosely surround the respective shafts 8 and 9. The printing wheel 10^a has a series of openings 20—see Fig. 5, through any one of which the screw 17 is projected in securing said printing wheels 10 and 10^a to the web 18. It will be seen that a single set of these fare-denomination printing wheels 10 and 10^a may be associated with a set of duplicate counters upon which are registered any other denomination of fares, for example, if the register is utilized for registering any particular denomination of fare, these printing wheels 10 and 10^a are adjusted to positions to print such denomination of fare and are then made secure in such position by the screw 17. As the register is now shown, the duplicate printing counters are utilized to register and print cash fares; should it become desirable to utilize said counters to register and print any other specific denomination of fares, for example, tickets, the printing wheels 10 and 10^a may be adjusted to the positions to bring the printing characters indicating tickets into printing alignment with the printing counters, and then be made secure in such position by means of the screw 17 penetrating the necessary opening 20 in wheel 10^a.

As thus far described, it will be seen that upon a single shaft there are mounted duplicate printing counters adapted to register and print a specific denomination of fare—to wit—cash fares, and associated with said printing counters are duplicate fare-denomination printing wheels 10 and 10^a. There are also mounted upon the same shaft duplicate date printing wheels consisting of month wheels 21 and 21^a and day wheels 27 and 27^a. These date wheels are loose upon the shaft 9 and are actuated to printing positions, at the beginning of each day's work by the following means: 28 and 28^a are finger wheels exposed on the outer side of the casing and bearing on their peripheries the names of the months and the dates. 31 is a stationary pointer lying across the peripheries of said wheels and serving to indicate the positions of the wheels in setting the same to the desired date; these wheels have

telescopic shafts 32 and 33. The inner shaft 33 is connected with the month wheel 28^a and is in alinement with the shaft 8 but has no connection therewith, and likewise the outer telescopic shaft 32 has no connection 70 with the shaft 8, said shaft 32 being connected with the date wheel 28. The inner shaft 33 is connected with the month wheel 28^a, and carries upon its inner end a spur wheel 34 which engages a spur wheel 35 75 fixed to the month printing wheel 21; the outer telescopic shaft 32 of the month wheel 28 has upon its inner end a spur wheel 36 which engages a spur wheel 37 fixed to the date printing wheel 27. 80

I have thus described the means for actuating one set of date printing wheels and will next describe the means for actuating the duplicate set of date printing wheels 21^a and 27^a which lie at the other extreme end 85 of the printing wheel shaft 9.

38 and 39 are spur wheels loose upon shaft 8 and meshing with spur wheels 40 and 41 of the duplicate set of date printing wheels 21^a and 27^a. Engaging the spur wheel 38 is 90 a smaller spur wheel 42 on shaft 43 and engaging the spur wheel 39 is a smaller spur wheel 44 on shaft 45, said wheels 42 and 44 being fast upon their respective shafts 43 and 45. These shafts 43 and 45 are mounted 95 parallel to each other and parallel to the shafts 8 and 9 in suitable bearings in the frame and are geared to the date finger wheels 28 and 28^a through spur wheels 46 and 47, the former being fixed to the shaft 45 and the latter being fixed to the shaft 43. The spur wheel 46 is engaged by the spur wheel 34 which as before stated, actuates the printing month wheel 21 directly. When the finger wheel 28^a is rotated, the duplicate 100 month printing wheels 21 and 21^a are simultaneously actuated through the spur wheels 34—35—46—44 and 39. Spur wheel 47 on shaft 43 engages spur wheel 36 on the inner end of the telescopic shaft 33 which as before 110 stated, is connected to the date finger wheel 28. As before stated, spur wheel 36 is also geared to spur wheel 37 of the date printing wheel 27, so that when the finger wheel 28 is rotated to set the duplicate date printing 115 wheels 27 and 27^a in the desired printing positions, the said date printing wheels are simultaneously rotated from the wheel 36 through wheels 36—37—47—42—38— and 40 respectively. 120

48 is a conductor's identification printing key or device which is insertible through a key opening 49 in a side of the casing and bears upon its inner end a printing character denoting the particular conductor who has 125 possession thereof; the other functions of this printing key are fully described in former patent No. 694,322 to which reference has already been made.

The duplicate records as shown in Figs. 7 130

and 8 are made from two separate rolls of paper 50 and 51 mounted in the base of the machine in alinement with each other. The webs from these rolls are withdrawn between 5 two feed rollers 52 and 53 above a pressure pad 54 which elevates said webs against the printing devices which are alined upon shaft 9, and which include the duplicate printing counters, the duplicate date printing wheels, 10 the duplicate fare-denomination printing wheels, and the conductor's identification printing key, and register identification devices. The pressure pad 54 is actuated by an eccentric bar 56, the latter being turned 15 by the key 56^a which is inserted in the key hole 56^b, and the printing devices are inked by an inking roller 55. The printing devices with the exception of the inking roller 55 are mounted upon side plates 56 which are 20 hinged at 57; these printing attachments are substantially the same as shown and described in former patents hereinbefore referred to.

Actuated simultaneously with the duplicate fare printing counters is a set of counters 58—59 and 60 which are otherwise known as "trip" or "passenger" wheels, and the purpose of which is to count or totalize the fares or passengers for a single trip or for any number of trips. These counters are of the well known construction being interconnected one with the other, so that the unit wheel will transfer to the tens wheel and the tens wheel will transfer to the hundreds wheel and 30 so on. The actuating member 13 through which the printing counters are operated is connected at its upper end to a link 61 which is pivoted to an actuating frame 62, which in turn, is loose upon the shaft 63 of said counters 58—59 and 60. The actuating frame 62 carries a ratchet pawl 64 which engages a ratchet wheel 65 fixed to the unit wheel 60 of said counters. These ratchet devices rotate continuously the unit wheel, and when one 45 complete rotation of said unit wheel is made, it picks up the tens wheel and moves it to the extent of one count and so on in a manner that is well understood. These trip or passenger counters are set to zero by imparting 50 movement to their shaft 63 from a finger piece 66 through gear wheels 67 and 68, the latter wheel being fixed to the counter shaft 63. In setting said counters to zero, the shaft 63 picks up each wheel and carries said 55 wheels in a body to their zero-setting positions, substantially as is described in my former patent No. 718,868 of Jan. 20, 1903.

Means are provided for compelling a complete movement of the individual actuating 60 member 13 and consists of a ratchet 69 made fast to the inner side of said member 13 and engaged by a pawl 70 which is pivoted to a lever 71, the latter being pivoted to a stationary part of the frame at 72, and controlled by a compression spring 73. Each

registration of duplicate fares is signaled upon a bell 74 through a hammer 75 which is actuated from a trip piece 76 engaged by a lug 77 carried upon the actuating member 13.

Fig. 7 indicates the conductor's record; 70 upon this record an impression of the conductor's identification key 48 is not made, but in lieu thereof each conductor signs his name to his own record and attaches the 75 number or mark of his key, for example, one statement or record is signed by John Doe whose key is identified by the mark 5^a, the other conductor whose name appears upon his individual record is Richard Roe whose key is identified by 7^a. The cashier or 80 inspector's record as shown in Fig. 8, contains an impression of the conductor's identification key which appears at the right hand column upon the record sheet.

While I have described my single fare register as utilized with a single denomination of fare, to-wit—cash fares, it will be understood that the same may be converted instantly to a single fare register for any other specific denomination of fare, the only change in the 90 entire machine necessary to so convert it, is the changing of the permanent indicator 3^a. The indicator holder 3^b is shown to contain a number of cards, any one of which may be utilized as a permanent indicator by removing the one in front.

The class or denomination of the fares registered and indicated in the register may be determined upon the records or statements taken from the machine by means other than 100 a printed or impressed character, for example, by using different colors of rolls of paper, a certain determined color being employed to designate or identify a certain class of fares, or the ink roll or rolls may be supplied 105 with different colored inks to print upon the paper the rolls of which are the same color.

I claim:

1. In a fare register, two sets of counters adapted to receive uniform step by step 110 movement in the operations of registering a single denomination of fares in duplicate, a set of actuating wheels for each counter, a shaft upon which said actuating wheels are mounted, a positively-actuated member engaging the primary actuating wheel of one set of said counter-actuating wheels and simultaneously actuating the primary actuating wheel of the other set of counter-actuating wheels through the movement imparted to the shaft upon which the counter-actuating wheels are mounted, and means for taking statements from both sets of counters showing in duplicate the number of fares registered on said counters.

2. In a fare register, two sets of counters, a set of actuating wheels for each set of counters, a shaft upon which said actuating wheels are mounted, a positively-actuated member to operate the primary actuating 130

wheel of the set of actuating wheels for one of said counters and simultaneously actuating the primary actuating wheel of the other set of counters through the movement 5 imparted to the shaft upon which both sets of counter-actuating wheels are mounted, an indicator common to both sets of counters, and means for taking statements from both sets of counters showing a duplicate record of the fares registered thereon.

10 3. In a fare register, a casing having two separate compartments, two sets of printing counters adapted to register a single class of fares in duplicate, means for taking duplicate statements from said counters, means for feeding said duplicate statements into the separate compartments in the casing, and a single-actuating member adapted to impart simultaneous movement to the two 15 sets of counters.

20 4. In a fare register, a casing having separate compartments, duplicate sets of printing counters mounted upon a common axis of rotation and adapted to register a single 25 class of fares, means for taking statements from said counters showing the fares registered thereon in duplicate, means for feeding said duplicate statements into the separate compartments in the casing, and a permanent indicator to exhibit the fares registered 30 on said duplicate counters.

35 5. In a fare register, a casing having separate compartments, two sets of printing counters mounted upon a common axis of rotation and adapted to register a single class of fares in duplicate, a fare-denomination printing device, means for taking a statement simultaneously from each counter and each fare-denomination printing device, 40 means for feeding the duplicate statements so taken into said separate compartments, and a single actuating member for imparting simultaneous movement to said counters in registering fares.

45 6. In a fare register, a casing having separate compartments, two sets of printing counters for registering in duplicate a single class of fares, a fare-denomination printing device, said counters and printing device being arranged upon a common axis, means for taking two original duplicate statements from said counters and printing device, and means for feeding said duplicate statements into the separate compartments of the casing.

55 7. In a fare register, two sets of printing counters, a set of actuating wheels for each set of counters, a shaft upon which said actuating wheels are mounted, a positively-actuated member adapted to operate one set of 60 counters through an engagement with the primary-actuating wheel thereof, and to operate the other set of counters through a movement of the primary-actuating wheel thereof which is imparted to said wheel 65 through the movement of the shaft, an iden-

tification printing device associated with the two sets of counters, and means for taking duplicate statements from said counters and an impression of the identification printing device.

70 8. In a fare register, two sets of counters, a set of actuating wheels for each set of counters, a shaft upon which said actuating wheels are mounted, an actuating member adapted to operate one set of counters 75 through an engagement with the primary-actuating wheel of said counters, and adapted to actuate the other set of counters by a movement of the shaft, a stationary indicator to indicate the fares of both sets of 80 counters, an identification printing device associated with said counters, and means for taking a statement from both sets of counters and the identification device.

85 9. In a fare register, a casing provided with separate compartments, two sets of printing counters for registering in duplicate a single class of fares, a fare-denomination printing device and date-printing devices, means for taking duplicate statements from said printing counters and devices, a permanent indicator to indicate the fares registered on said duplicate counters, and means for feeding said duplicate statements into the separate compartments 90 in the casing.

95 10. In a fare register, two sets of printing counters, a set of actuating wheels for each set of counters, a shaft upon which said actuating wheels are mounted, a totalizing 100 counter, an actuating member adapted to operate one set of counters through a movement of the primary-actuating wheel thereof, and to operate the other set of counters through a movement imparted to the primary-actuating wheel thereof from the 105 shaft, connections between said actuating member and the totalizing counter to operate the latter simultaneously with the operations of the printing counters, and 110 means for taking statements from the two sets of printing counters.

11. In a fare register, a casing provided with separate compartments, two sets of printing counters for registering in duplicate a single class of fares, means for taking statements from said counters, one being a duplicate of the other and both being original statements, means for feeding said duplicate statements into the separate 120 compartments in the casing, a totalizing counter to register the sum of the fares registered on the duplicate counters, and means for simultaneously actuating the duplicate counters and the totalizing counter. 125

12. In a fare register, a casing provided with two separate compartments, two sets of printing counters for registering in duplicate the same class of fares, means for taking statements from said counters, one 130

being a duplicate of the other and both statements being original statements, means for feeding said statements into the separate compartments in the casing, a fixed indicator to exhibit the fares, and a totalizing counter to count the sum of the fares registered on the duplicate counters.

13. In a fare register, a casing having separate compartments, two sets of printing counters to register in duplicate the fares collected, two sets of actuating wheels for said counters, a shaft upon which said actuating wheels are mounted, an actuating member operating one set of counters by a movement imparted to the primary-actuating wheel thereof, and operating the other set of counters through a movement imparted to the shaft, means for taking statements from said counters showing in duplicate the fares registered thereon, and means for feeding said duplicate statements into the separate compartments in the register casing.

14. In a fare register, two sets of printing counters adapted to register fares of a single class in duplicate, a set of actuating wheels for each counter, an operating member imparting simultaneous movements to said counters through the operation of the primary-actuating wheel of one set of counters, and the operation of the primary-actuating wheel of the other set of counters through the movement imparted to the shaft upon which the actuating wheels are mounted, means for taking statements from said counters, and printing devices by means of which the person or persons taking such statements are identified therewith.

15. In a fare register, duplicate sets of printing counters, a set of actuating wheels for each set of counters, a shaft upon which said actuating wheels are mounted, and to which the primary-actuating wheel of each set is fixed, an actuating member engaging one of said primary-actuating wheels and imparting simultaneous movement to the two sets of counters through said primary-actuating wheel and the shaft, duplicate fare-denomination printing devices, duplicate date-printing devices, and means for taking statements from said printing counters showing a duplicate statement of the fares collected, and a duplicate statement of the denomination of such fares and of the date upon which such statements are taken.

16. In a fare register, duplicate sets of printing counters, a set of actuating wheels for each set of counters, a shaft upon which said actuating wheels are mounted, a date-printing device associated with each set of printing counters, an actuating member adapted to impart simultaneous movement to said counters from the movement imparted to the primary-actuating wheel of one set of counters and to the primary-actuating wheel of the other set of counters through a

movement of the shaft, and means for taking statements from the printing counters and the date-printing devices.

17. In a one fare register, duplicate printing counters mounted in printing alinement, a conductor's identification device in printing alinement with the duplicate printing counters, a single-actuating member for said duplicate counters, an auxiliary shaft parallel with the duplicate counter shaft, means on said auxiliary shaft engaged by the single actuating member and through which one of said duplicate printing counters is operated directly from the single actuating member, and means on said auxiliary shaft through which the other of said duplicate printing counters is actuated from the movement of said auxiliary shaft imparted by the single actuating member.

18. In a fare register, duplicate sets of printing counters, a set of actuating wheels for each set of counters, a shaft upon which said actuating wheels are mounted, a fare-denomination printing device, a totalizing counter, an actuating member adapted to impart simultaneous movements to said counters from the movement imparted to the primary-actuating wheel of one set of counters, and from the movement imparted to the shaft, connections between the totalizing counter and said operating member, and means for taking statements in duplicate from the printing counters, and the fare-denomination printing device.

19. In a fare register, two sets of printing counters for effecting duplicate registrations of a single class of fares, duplicate date-printing devices, means for taking duplicate statements from said counters and date-printing devices, means for simultaneously actuating both sets of counters uniformly and to the same extent in each operation of registering the fare collection, said operating means being limited to the same extent of movement in each of its operations, and means for rotating the duplicate date-printing devices simultaneously.

20. In a fare register, two sets of printing counters upon which are registered duplicates of a single class of fares, duplicate fare-denomination printing devices mounted in permanent printing alinement with said counters, means for taking duplicate statements from said counters and fare-denomination printing devices, and means for simultaneously actuating said counters to the same extent in registering each fare collection.

21. In a fare register, a casing having two record compartments, two sets of fare printing counters for registering in duplicate a single class of fares, means for taking printed records in duplicate from said counters, means for feeding said duplicate records into the record compartments in the register,

- means under the control of the conductor enabling the removal by him of one of the records from one of said compartments, means under the control of the cashier or inspector enabling the removal by him of the other of said records from the other record compartment, and a permanent indicator for exhibiting the fares registered on said counters and indicated on said duplicate records.
10. 22. In a fare register, two sets of fare printing counters for registering and printing duplicates of a single class of fares, means for taking duplicate statements from said counters, a permanent fare indicator to exhibit the 15 class of fares registered on said counters, a totalizing counter to register and indicate the totals of the fares, signal devices, a common operating member for simultaneously actuating the duplicate printing counters, the 20 totalizing counter, and the signal devices.
23. In a fare register, two sets of printing counters for registering in duplicate a single class of fares, date printing devices, means for taking duplicate printed records from 25 said counters and date printing devices, means enabling the conductor to remove one of said printed records from the register, means enabling the cashier or inspector to remove the other of said records, means for 30 simultaneously setting the duplicate date-printing devices to printing positions, means for simultaneously actuating the duplicate sets of printing counters to printing positions and registering fares, and a permanent fare 35 indicator.
24. In a fare register, two sets of printing counters for registering in duplicate a single class of fares, a single operative means for imparting to said counters a uniform extent 40 of movement in registering each fare collection in duplicate, date-printing devices in duplicate, register-identifying printing devices in duplicate, means for taking duplicate printed records from said counters and devices, and a permanent indicator to indicate 45 the class of fares registered on said counters.
25. In a fare register, two sets of printing counters for registering in duplicate a single class of fares, date-printing devices, register- 50 identifying printing devices, means for simultaneously setting to printing positions the date-printing devices, means for taking duplicate printed records or statements from said counters and printing devices, means 55 under the control of the conductor enabling the removal of one of said statements, means under the control of the cashier or inspector enabling the removal of the other of said statements, means for identifying the conductor with one of said statements, and a 60 permanent indicator for exhibiting the class of fares registered on said counters.
26. In a fare register, two sets of printing counters for registering in duplicate a single 65 class of fares, duplicate date-printing devices, duplicate fare-denomination printing devices, duplicate register-identifying printing devices, means for taking duplicate printed statements from said counters and printing devices, means for simultaneously setting 70 to printing positions the duplicate date-printing devices, means for simultaneously actuating the duplicate fare-printing counters, means under the control of the conductor enabling him to remove one of said duplicate 75 statements, means under the control of the cashier or inspector enabling him to remove the other of said duplicate statements, and a permanent indicator to exhibit the fares registered on said counters. 80
27. In a fare register, two sets of fare-printing counters for registering in duplicate a single class of fares, duplicate fare-denomination printing devices, duplicate date-printing devices, and duplicate register-identifying 85 printing devices mounted upon a common axis, means for taking duplicate printed statements from said counters and printing devices, means under the control of the conductor enabling him to remove one of said 90 printed statements, means under the control of the cashier or inspector enabling him to remove the other of said duplicate statements, means for identifying the conductor with the statement removable by the cashier 95 or inspector, and a permanent fare indicator to exhibit the fares registered. 99
28. In a fare register, the combination with fare-printing counters, a visible fare indicator, and a fixed printing character to 100 designate the fare indication.
29. In a fare register, the combination of fare-printing counters, a fare indicator, and a fixed printing character, said printing character to determine the class of fares registered. 105
30. In a fare register, the combination of fare-printing counters, a single operative means for imparting to said printing counters the same extent of movement in each operation of registering the fare collections, a fare indicator, a fixed printing character, and means for taking prints or impressions from the counters and from the printing character to determine the number and the class of 110 fares registered. 115
31. In a fare register, a fare indicator fixed adjacent to said register, fare-printing counters to print the number of fares registered, and a printing character permanently in 120 printing alinement with said printing counters to designate the class of fares as shown by the fare indicator. 125
32. In a fare register, the combination with fare-printing counters, a visible fare indicator, a printing character to designate the fare indication, said fare printing character being in permanent printing alinement with

he counters, and a printing character to indicate the date of the statements or impressions taken.

33. In a fare register, the combination with fare-printing counters, a fare indicator, a printing character, said printing character to determine the class of fares registered and being permanently in printing alinement with the printing characters, and a printing character to indicate the date of the statements or impressions taken.

34. In a fare register, the combination of fare printing counters, a fare indicator, a printing character permanently in printing alinement with the printing counters, means for taking prints or impressions from the counters and from the printing character to determine the number and class of fares registered, and a printing character to indicate the dates of the statements or impressions taken.

35. In a fare register, a fare indicator fixed adjacent to said register, in combination with fare-printing counters to print the number of fares registered, a printing character to designate the class of fares as shown by the fare indicator, the same being permanently in printing alinement with the fare printing counters, and a printing character to indicate the dates of the statements or impressions taken.

36. In a fare register, the combination of fare-printing counters, a visible fare indicator, a printing character to designate the fare indication, said printing character being fixed in printing alinement with the printing counters, and a printing character to designate the trip number.

37. In a fare register, the combination of fare-printing counters, a fare indicator, a printing character, said printing character being in permanent printing alinement with the fare-printing counters and adapted to designate or determine the class of fare reg-

istered, and a printing character to designate the trip number.

38. In a fare register, the combination of printing counters, a fare indicator, a printing character to denote the class of fares registered upon the counters, means for taking prints or impressions from the counters and the printing character to determine the number and the class of fares registered, and a printing character to determine the trip number. 55

39. In a fare register, a fare indicator fixed to or adjacent to said fare register, fare-printing counters to print the number of fares registered, a printing character to designate the class of fares shown by the fare indicator, said printing character being in permanent printing alinement with the fare-printing counters, and a printing device to designate the trip number. 60

40. In a fare register, a fare indicator fixed to or adjacent to said said fare register, said fare indicator to show the class of fares to be registered, fare-printing counters to show the number of fares registered, and means for designating on the statements or impressions taken the class of fares registered, said means comprising a printing character which is permanently in printing alinement with the printing characters. 70

41. In a fare register, two sets of printing counters to register in duplicate the fares of a single denomination, means for taking duplicate records from said counters, a permanent printing character to designate said fare denomination on every record taken 80 from said counters, and a fixed indicator to exhibit such single denomination of fare.

In testimony whereof I affix my signature, in presence of two witnesses.

JOHN F. OHMER.

Witnesses:

C. M. THEOBALD,
MATTHEW SEIBLER.
